UNITED STATES PATENT OFFICE.

JAMES A. HOUSE, OF BRIDGEPORT, CONNECTICUT.

APPARATUS FOR FORMING AND SHAPING CORSETS.

SPECIFICATION forming part of Letters Patent No. 288,637, dated November 20, 1883.

Application filed April 23, 1883. (No model.)

To all whom it may concern:

Be it known that I, JAMES ALFORD HOUSE, of Bridgeport, county of Fairfield, and State of Connecticut, have invented Improvements 5 in Apparatus for Forming and Shaping Corsets, of which the following description, in connection with the accompanying drawings, is a specification, like letters on the drawings representing like parts.

10 In this invention I employ a divided form pivoted or mounted upon levers or supports, co-operating with which is a spreader and an equalizer, the spreader being herein shown as a right-and-left-threaded screw and the equalizer as composed of links and a stud or pin traveling in or upon a guide. As the upper ends of the levers are separated to expand or separate the two parts of the corset-form, the links of the equalizer, with their connecting pin or 15 stud in a guide, prevent the form parts from tipping over unequally, and insure equal movement of the two parts of the form. Each form, preferably made hollow and of metal, is provided with a series of studs or hooks to receive the eyeleted edges of the corset when the latter is being finished, and at such time the usual hooks and eye-pieces of the corset-steels are properly engaged one with the other. The 20 form may be heated by gas or other flame or 25 by steam, as may be desired.

My invention consists, essentially, in a divided form and levers to engage or support the same, combined with a spreader, to actuate the said levers and expand the corset-form; also, in a divided form, levers to engage 35 it, and a spreader, combined with equalizing mechanism to insure equal movement of the two parts of the form when being separated or spread apart.

40 Figure 1 is a front elevation, partly broken out, of a corset-finishing apparatus embodying my invention; Fig. 2, a broken side elevation; and Fig. 3, a detail of the edges of the two parts of the form at the back, to show the studs or pins with which the eyelets of the corset 45 are engaged.

The frame A of the machine, of suitable shape to sustain the working parts, has suitable bearings to support the rods or pins a a, 50 which serve as the fulcra for the levers b b', which, as herein shown, have their upper ends

rounded and entered into slots or pockets formed in the inner or contiguous faces of the two parts c c' of the form, the said parts being preferably made of metal and hollow, for the 55 sake of lightness, and also so as to enable them to be heated by a gas-flame, as at d, from a gas-burner, d', or it might be a Bunsen burner adapted to commingle gas and air, or to be heated by the flame of a lamp, e, or it might 60 be a steam-pipe led into the said form parts. The lower ends of the levers b b' are provided with or loosely engage nuts f f' on a shaft, g, supported in suitable bearings and having a right-and-left hand thread, so that rotation of 65 the said shaft in one or the other direction will cause the upper ends of the said levers to approach each other or to move away from each other, the latter movement causing the form parts c c' to separate and stretch and 70 shape the corset applied about them, as will be described. The dotted lines, Fig. 1, show the position of the levers when the form acts to stretch and shape a corset. The screw forms an expanding device for the levers and 75 form, and in place of it I may use any well-known equivalent. The frame has an attached guide, h, herein shown as a slotted metal plate, which receives a pin or stud, h', placed at the junction of, and which serves to connect, the lower ends of the two links m m', which form what I denominate the "equalizing mechanism." The upper ends of these links are pivoted or connected at n n' to the 80 form parts at their lower portions, so that as 85 the form is expanded and the pin or stud h' rises in the guide the links of the equalizing device so hold the parts c c' that one cannot move farther than the other, and thereby the corset is equally stretched from a common center line.

The corset is not herein shown, but it will be of usual form. The hooks and eyes attached to its steels will be engaged one with the other, and the usual eyelets of the eyeleted edges, which receive the usual lacing-cord, will be placed over the pins or studs o o', and then the spreader or screw g will be turned to separate the upper ends of the levers b b' and expand the form, thus stretching and shaping 100 the corset to the shape of the form.

It is obvious that the form might be expand-

ed by moving but one of the levers b or b' ; but the result would not be as satisfactory and desirable as to move both of the said levers, and it is best to move each of them the same distance.

The studs o o' , attached to the parts c c' of the form, are extended outwardly from the sides of the form parts, as in Fig. 3, so as to get under the eyeleted edges of the corset.

10 I claim—

1. In a corset-finishing apparatus, a divided form, levers to support the same, and a spreader to operate the said levers and separate the two parts of the form, substantially as described.

15 2. In a corset-finishing apparatus, a divided form provided with studs or pins, two levers to support the said form, and a spreader to

operate the said levers and separate the two parts of the form, substantially as described. 20

3. The divided form, levers to support the same, and a spreader to operate the said levers and separate the said form, combined with an equalizer, to operate substantially as described. 25

4. The divided hollow form parts, and the links, pin or stud and guide, combined with the two levers, and spreading devices, substantially as described.

In testimony whereof I have signed my name 3c to this specification in the presence of two subscribing witnesses.

JAMES ALFORD HOUSE.
